UNITED STATES PATENT OFFICE.

PETER WEBER, OF ORANGE, NEW JERSEY, ASSIGNOR TO NEW JERSEY PATENT COMPANY, OF WEST ORANGE, NEW JERSEY, A CORPORATION OF NEW JERSEY.

DESIGN FOR A PHONOGRAPH-CABINET.

40,347.

Specification for Design.

Patented Nov. 9, 1909.

Application filed September 11, 1909. Serial No. 517,348. Term of patent 14 years.

To all whom it may concern:

Be it known that I, PETER WEBER, a citizen of the United States, residing at Orange, in the county of Essex and State of New Jersey, have invented a new, original, and ornamental Design for Phonograph-Cabinets, of which the following is a specification, reference being had to the accompanying drawing, forming a part thereof.

The figure is a perspective view of a

phonograph cabinet showing my new design.

I claim:

The ornamental design for a phonograph cabinet, as shown.

PETER WEBER.
